TIME RELEASE APPARATUS

Peter Beghetti, San Francisco, Calif.

Application December 14, 1932, Serial No. 647,110

5 Claims. (Cl. 161—1)

This invention relates to devices which may be set for performing an operation at any future time. The main objects of the invention are to provide an improved timing and operating device of this kind which will be simple, which cannot get out of order, and one which once started or set cannot fail to operate at the time for which it is set. Another object is the provision of a timing device as above which will automatically turn off a gas valve such as the gas valve of a stove or oven so as to stop the cooking when a certain time comes around.

Other features and advantages of the invention will appear in the following description and accompanying drawing.

Briefly described, the invention consists of a box housing, a burning member such as a candle, and when the candle burns down to the point for which it is set, it releases a weight which falls and performs the work.

In the drawing, Fig. 1 is a side elevation of my device arranged to shut off a gas stove valve and with the front side of its enclosing box taken off to show the internal construction.

Fig. 2 is a sectional view of the device as seen from the lines 2—2 of Fig. 1.

Fig. 3 is an elevation of the candle used to actuate the device.

Figs. 4 and 5 are respectively the plan and side views of the candle release clip.

Fig. 6 is a view similar to that of Fig. 5 except that it shows the use of a punk instead of a candle.

Fig. 7 is an enlarged view of the gas stove valve handle fitted with a detachable cord or chain attachment.

In more detail, the drawing shows at 1 a rectangular sheet metal box provided with a hinged upper lid 2 and a removable side panel 3 which has a lip 4 projecting outwardly at its upper edge to serve as a grip for lifting it from free sliding grooves formed in the corners of the box to receive it.

The lid 2 and the lower part of one or more sides of the box are perforated as at 5 to ventilate for the burning candle 6 which forms the timing element of the combination.

The candle 6 is of a fairly hard grade of standard size and preferably has cross graduations 7 extending along its side each of which designates a certain time interval of burning—say ten or fifteen minutes. This candle is supported on a stand 8 which may be adjusted up and down on a fixed rod by means of a thumb screw 10. The rod 9 may conveniently have

graduations 11 on it as described for the side of the candle, so that ungraduated candles or special punks may be used.

When the candle is in position it projects upwardly through a hole in a transverse sheet metal partition 12 and through a flat sheet metal yoke 13 hooked over a hook 14, and also through a hole in a flat plate 15 which is positioned between the arms of the sheet metal yoke and is attached to a chain 16 which passes along above the partition 12 over a pulley 17 at the end of the box, up over a pulley 18 at the top of the box, then down, and secures to a heavy block of iron 19 or other weight which hangs suspended and furnishes the stored power for performing the required operation when released by burning of the candle as will be later explained.

Also attached to the weight 19 is an operating cord or chain 20 which passes over any number of guide pulleys as at 21, 22 and leads from the latter in any desired direction as indicated by the dotted lines a, b, c, to the work to be performed, or as shown in the present instance at 20 to the handle 23 of a gas valve of a gas stove or oven 24. The connection to the gas valve handle is preferably made by means of a detachable shoe 25 as of leather or other material which is slipped over the handle and laced, buttoned or otherwise secured in place.

In operation, with all parts arranged as shown in Fig. 1 and the box preferably secured to the floor or other firm support as by screws 26, the side panel 3 is opened and the candle is adjusted vertically so as to project above the yoke 13 the proper number of graduations corresponding to the future time at which it is desired to shut off the gas stove, or this may be determined from the graduations on the stand 9. The candle is then lighted and the box closed, and when the candle burns down to the plate 15 the plate will slide past the candle and permit the weight to drop and thereby pull on chain 20 and turn off the gas valve. Chain 20 is preferably made slightly longer than necessary so as to keep a certain amount of slack in it as indicated at 20' so that the falling weight will give a more sudden pull upon taking up the slack and thus get the valve started if it should be stuck.

The distance of falling of the weight may be adjusted by providing a hook link 16' in chain 16 which can be hooked into any of the remaining links as indicated in Fig. 5.

As plate 15 slides over the end of the burning candle it will put out the flame as the flat part of the plate passes over it.

Instead of a candle to form the timing element a punk or slow burning fuse may be used. Such a fuse or punk would be much smaller in diameter than a candle and to properly accommodate this the yoke 13 and plate 15 are provided with a smaller hole 27 to approximately fit the fuse or punk 28 (see Fig. 6), and the lower end of the punk could be supported, if necessary, on an extension 8' of the candle support.

Having thus described my invention it will be seen to be a very reliable device for automatically shutting off a gas stove at any predetermined future time, as it cannot fail or get out of order like the spring timers frequently do, with a result that the stove burns up a carefully prepared dinner during the absence of the party in charge, and while its principal use is for the purpose mentioned it is evident that it may be used to turn on or off an electric switch handle for heat or light, or a radio, or turn on an alarm or other device. It should also be noted that while I prefer a weight as the source of stored power, a spring could be substituted for it, though it would not be so reliable.

I claim:—

1. Time release apparatus comprising a ventilated box, a candle support therein, means engaging the candle to prevent deflection thereof, a device engaging around the candle, a weight, means connected to said device suspending said weight in a manner to drop the weight when the candle burns to the device, and means operated by the falling weight for doing work at a remote point.

2. Apparatus as specified in claim 1 in which means is provided for adjusting said candle for different lengths of burning before reaching said device.

3. Apparatus as specified in claim 1 in which the means engaging the candle is a flat metal yoke, and said device is a metal plate adapted to go between the arms of said yoke, the yoke and plate being apertured to pass the candle.

4. Apparatus as specified in claim 1 in which the means engaging the candle is a flat metal yoke, and said device is a metal plate adapted to go between the arms of said yoke, the yoke and plate being apertured to pass the candle.

5. In a time release apparatus, a timing element comprising a generally vertically extending elongated candle, means arranged and adapted to engage the candle at a point intermediate its ends and arranged and adapted to hold the candle against lateral movement while permitting relative movement therebetween in opposite directions longitudinally of the candle, said means comprising a stationarily mounted member provided with an aperture to pass the candle therethrough with a side of the candle engaging a side of the aperture, a movable device adjacent said member blocked from movement by the body of the candle adapted to be released upon burning of the candle to said movable device, a support arranged and adapted to engage the lower end of said candle below said member, and means mounting said support for movement axially of the longitudinal axis of the candle for supporting the candle at various heights through the aperture in said member as desired.

PETER BEGHETTI.
